Attorney

UNITED STATES PATENT OFFICE.

ERNEST WYKES, OF HUMBOLDT, IOWA.

RADIATOR.

Application filed July 13, 1922. Serial No. 574,611.

To all whom it may concern:

Be it known that I, ERNEST WYKES, a citizen of the United States, residing at Humboldt, in the county of Humboldt and 5 State of Iowa, have invented certain new and useful Improvements in Radiators; and I do hereby declare the following to be a full, clear, and exact description of the invention, such as will enable others skilled in 10 the art to which it appertains to make and use the same.

Radiators for heating systems utilizing steam, hot water, vapor and the like result in discoloration of the walls and ceilings of 15 rooms, hallways and other places where located, and frequently the air is rendered dry and unfit for respiratory purposes and causes interior woodwork to crack and warp.

The present invention aims to prevent discoloration of walls and ceilings and soiling of draperies and to secure a better circulation and a more uniform distribution of the heat and to render the air humid or moist, this being effected by deflecting means in 20 conjunction with the radiator whereby the hot air is directed outwardly into the room and away from the wall against which the radiator is placed and the provision of a pan for containing water which is located 25 so as to be out of the way and hidden from view and yet readily accessible to be replenished with water and to be cleaned as occasion may require.

Other objects and advantages will be apparent and suggest themselves as the nature of the invention is understood.

While the drawings illustrate an embodiment of the invention it is to be understood that in adapting the same to meet different 40 conditions and requirements, various changes in the form, proportion and minor details of construction may be resorted to without departing from the nature of the invention.

45 Referring to the accompanying drawings forming a part of the application,

Figure 1 is a front view of the upper portion of a radiator embodying the invention,

Figure 2 is a top plan view, parts being 50 broken away,

Figure 3 is a rear view of the upper portion of the radiator, parts being broken away, and

Figure 4 is a sectional detail on the line 55 4-4 of Figure 1.

Corresponding and like parts are referred

to in the following description and designated in the several views of the drawings by like reference characters.

The radiator illustrated may be of any 60 construction usually employed for heating purposes and utilizing steam, hot water or vapor, and comprises a plurality of loops or columns 1 placed side by side and connected in any usual way. In accordance 65 with the present invention, a fin or web 2 is provided at the side of the upper portion of each of the loops and inclines upwardly and forwardly from the rear as indicated most clearly in Figure 4 whereby to deflect 70 the ascending current of hot air forwardly and away from the wall against which the radiator is usually placed. The end columns or loops 1 have the webs or fins 2 upon their inner side only, whereas the intermediate 75 columns or loops are provided with corresponding fins or webs upon both sides. The fins or webs 2 are disposed wholly below the top of the radiator so as to be out of the way and practically hidden from view and to allow the top of the radiator to be used as a shelf or table. The fins or webs 2 are preferably cast as a part of the loop or column, but it is obvious that they may be provided in any manner, the object being to 80 make a practically tight joint between the sections so as to deflect the air outwardly into the room.

Heating radiators are usually placed adjacent a wall 3 and are spaced therefrom. 90 A hood is provided and is attached to the rear side of the radiator and extends therefrom to the face of the wall 3. As shown, this hood comprises a fixed section 4 and an adjustable section 5. The fixed section is attached to the radiator and the section 5 has adjustable connection with the section 4, whereby the hood may be adjusted to any variation in the space between the radiator and wall 3, or the hood may be made in one 95 piece of flexible material to allow adjustment. The hood inclines upwardly and forwardly and forms a continuation of the webs or fins 2. The ascending current of hot air is deflected outwardly into the room and away from the wall by the hood and the webs or fins, thereby preventing discoloration of the wall and ceiling and obtaining a 100 more uniform distribution of the heat and moisture.

A water pan 6 is attached to the rear side of the radiator in a manner to be readily re-

moved. Panels 7 are in line with the end loops or columns of the radiator and are detachably connected thereto and are disposed to terminate below the hood. By having the 6 panels 7 detachable, the pan 6 is readily accessible to be replenished with water or to be cleaned as occasion may require.

What is claimed is:

1. In combination with a radiator, a deflector disposed wholly below the top thereof and comprising a portion arranged between the loops or columns and a portion in the rear of the radiator to extend across the space formed between the wall and radiator, 10 and panels in the rear of the end columns or loops and closing the space in the rear of the radiator and below the rear portion of the deflector.
- 15 2. A radiator comprising a plurality of

loops disposed side by side in spaced relation, a deflector adjacent the top of the radiator and below said top and disposed between the loops and extending from the rear to the front of the radiator in an upward and forward inclination, and a hood wholly 25 in the rear of the radiator and inclining rearwardly and downwardly and comprising a fixed section attached to the loops in line with the deflector, and an adjustable section carried by the fixed section and adapted to 30 touch the wall adjacent and in the rear of the radiator.

In testimony whereof I affix my signature in presence of two witnesses.

ERNEST WYKES.
